United States Patent Office

Des. 189,240
Patented Nov. 15, 1960

189,240

CHAIR

Robert H. Solomon, Chicago, Ill., assignor to National Metalwares, Inc., a corporation of Illinois

Filed Sept. 25, 1959, Ser. No. 57,698

Term of patent 7 years

(Cl. D15—1)

Fig. 1.

Fig. 2.

The dominant features of the design are shown in the drawing in full lines.

I claim:

The ornamental design for a chair, substantially as shown and described.
